BOILER BAFFLE

Application filed April 4, 1928. Serial No. 267,208.

This invention relates to baffles for boilers and is concerned particularly with baffles for water-tube boilers of the so-called horizontal type. In boilers of this type the hot gaseous products of combustion issuing from the grate, fuel nozzles, or the like, are commonly conducted longitudinally along the boiler tubes by means of suitable longitudinal baffles and then the gases traverse the water drum before passing through the flue to the stack. In another common form of horizontal boiler the baffles are arranged transversely of the boiler tubes so that the gases are conducted across the tubes in alternate directions along a sinuous path before passing out through the stack. Various other forms of baffle arrangements for horizontal boilers have also been employed but in each arrangement a large proportion of the heat of combustion passes out through the flue and is lost because the velocity of the gases is greater than the rate of heat transfer or absorption of the heat by the water in the boiler. This rate of heat transfer is theoretically considered to be proportional to the square of the velocity of the gases, and it is further contended that this desirable relatively high velocity of the gases has a scouring effect on the surfaces of the boiler tubes which removes or prevents the formation of the skin of air or dead gases which is a poor conductor of heat and therefore diminishes the rate of heat transfer. However, I have found that a greater thermal economy is obtainable in a boiler when the velocity of the gases is decreased at certain points in their path, so that, while the scouring effect on the tubes is not greatly diminished, the gases are in contact with the tubes for a greater period of time, whereby the rate of heat transfer between the gases and the water in the tubes is increased and the temperature of the flue gases is materially decreased, and it is the object of this invention to provide means for accomplishing this purpose.

In accordance with this invention horizontal water tube boilers are provided with baffles which permit the gases to traverse the boiler tubes in part at relatively high velocity so that their scouring effect is utilized, and permit the gases in part to traverse the tubes at relatively low velocity so that the net period of contact between the hot gases and the boiler tubes is increased and the gas circulation made more thorough, whereby the rate of heat transfer between the gases and the water and the quantity of heat so transferred is increased. The arrangement of the baffles for this purpose consists in placing one baffle along the lower rows of tubes from the front to a short distance from the rear of the boiler so that the gases enter the bank of tubes at the rear, a second baffle along the upper tubes from the rear to a short distance from the front of the boiler, so that the gases may pass from the bank of tubes at the front, and a third or apron baffle extending from the second baffle at the front of the boiler at an angle so that the gases are deflected downwardly before leaving the bank of tubes at the front. The angle between the second and third baffles creates a pocket beneath the second baffle in which a portion of the gases accumulate while other gases pass below the third baffle without entering this pocket, but this angle is made obtuse with respect to the second baffle so that the gases are not trapped in the pocket and damaging explosions cannot occur. Accordingly, as the gases which accumulate in the pocket cool by transferring their heat to the water in the adjacent tubes, their density increases so that they fall downwardly in the form of a curtain to be replaced by other hot gases coming from the rear. As these cooling gases continually fall while transferring their heat to the tubes, they are eventually caught by the current of gases flowing below the edge of the third baffle and carried out to the stack. Auxiliary baffles projecting upwardly from the upper baffle and downwardly at the flue may be provided in accordance with the type of fuel burned under the boiler. For example, when burning long-flame anthracite coal under the boiler, which imparts greater velocity to the gases, other things being equal, it is advisable to introduce one or more of the auxiliary baffles described, while the bituminous and lignite coals, the pulverulent, gaseous and liquid fuels and the like, require a

different arrangement of these auxiliary baffles in order to obtain the best thermal efficiency in the boiler.

As an alternative or auxiliary installation when low volatile fuels whose radiant heat is relatively high, such as anthracite, coke-breeze, lignite or the like, are employed, the lowermost baffle is spaced from the lowest row of tubes, that is, it is placed along the third, fourth, fifth, or other row from the bottom so that these lower tubes are exposed to the radiant heat issuing from the grate. In order that such volatile gases as are given off by the fuel may be ignited before passing out with the other gases of combustion, a pocket similar to that previously described is formed under the lower baffle by providing an apron baffle extending from the free rear end of the lower baffle at an angle across the lower tubes into the gas passage. The volatile gases are ignited while in this pocket and are deflected downwardly in the form of a curtain to pass out of the pocket with the draft below the lower edge of the apron baffle. These hot, deflected gases may be allowed to impinge upon a superheater placed below the lower edge of the apron baffle.

For a better understanding of the invention, reference is made to the accompanying drawing in which Figs. 1 and 2 illustrate the arrangements for horizontal boilers, which constitute this invention. In Fig. 1, a conventional design of a horizontal water tube boiler is illustrated, in which numeral 10 designates the water drum from which depend the front and rear water legs or headers 11 and 12, respectively. The water tubes 13 extend between the headers to form the bank in the usual manner. This boiler structure is suitably mounted in masonry including front and rear walls 14 and 15, respectively, and a lining of refractory material such as fire-brick. The stack rises above the flue 16 at the rear and the charging and ash doors and the grate 17 are usually placed beneath the front portion of the boiler, but if pulverized coal, gas, oil and the like are used, other constructions are necessary.

Traversing the lower row of boiler tubes 13 from the front to within a short distance of the rear of the boiler, leaving passage 18, is lower baffle 19 which conducts the gases rearwardly into passage 18 and permits proper combustion of the fuel gases before they enter the bank of tubes. An upper baffle, 20, extends along the upper row of tubes from the rear to within a short distance of the front of the boiler, leaving passage 21. Extending at an angle from the front end of upper baffle 20 is an apron baffle 22 formed around the boiler tubes which it traverses and consisting preferably of initially plastic refractory material cast or moulded in position. The spaces between the lower and front edges of apron baffle 22 and lower baffle 19, and

front header 11 are preferably made equal so as to provide a uniform gas passage around the apron baffle 22, and the dimension of this passage varies with the conditions of use, type of fuel, and the like. The angle between the apron baffle 22 and upper baffle 20 is made obtuse so that, although a pocket 23 is formed between these baffles, no gases can be trapped therein.

The hot gases of combustion pass from grate 17 in the direction of the heavy arrows through passage 18, and into the bank of tubes across the rear to the top of the bank where they are turned forward by the upper baffle 20. The gases then travel longitudinally of the tubes, part of them passing with relatively high velocity around the edge of the apron baffle 22, whereby they are conducted across the front portions of the tubes, through passage 21, and traverse the under surface of water drum 10 before passing to the stack by way of flue 16. The remainder of the gases collect behind apron baffle 22 in pocket 23. As these gases cool in transferring their heat to tubes around which they circulate, their density increases so that they fall downwardly in the direction of the dotted vertical arrows in the form of a curtain, being replaced continuously by hotter gases entering pocket 23 along upper baffle 20 from the rear. This curtain of relatively slowly circulating gases extends from a point located approximately at 24 on the upper baffle to the lower edge of apron baffle 22, this curtain being defined by the phantom line in the drawing which represents the approximate edge of the current of gases which pass directly through the bank of tubes and around the edge of apron baffle 22 in the manner indicated by the heavy arrows. These descending gases gradually pass into the gas current to be carried away thereby.

The hot gases which collect in pocket 23 are in contact with the boiler tubes about which they circulate for a sufficient period of time to transfer the greater proportion of their heat content to the tubes. Their circulation while confined to the pocket is sufficiently active to produce a scouring effect on the tubes to prevent the formation of the skin of dead gases which is a poor conductor of heat. This is so because the velocity of the hot gases entering the pocket from the rear along the under side of upper baffle 20 is relatively high and continuous in a forward direction.

The net results of action of the descending curtain of gases in the pocket behind apron baffle 22 and that of the current of gases flowing under the edge of baffle 22 is to retard the flow of gases as a whole, so that, in general, the area of the gas passages after the gases leave baffle 22 need not be greater than the area of the passage around the edge of baffle 22, and therefore the area of flue 16 need not

be greater, thereby effecting a considerable saving in space, weight and construction costs.

Depending upon the type of fuel used, auxiliary baffle 25 rising above the forward end of upper baffle 20 at its point of connection with apron baffle 22, and auxiliary baffle 26 extending from the flue 16 may be employed, these auxiliary baffles being shown in phantom in the drawing. The effect of either and both of these auxiliary baffles is the further retardation of the flow of the gases, thereby allowing a longer period of contact between the gases and the heating surfaces of the boiler. For example, if long-flame or highly volatile fuels are employed, auxiliary baffle 25 alone may be used in conjunction with baffles 19, 20 and 22 to keep the gases in contact with the bank of tubes for a longer time, while the gases after passing auxiliary baffle 25 increase in velocity to the flue 16. Similarly, if auxiliary baffle 26 alone is used in conjunction with baffles 19, 20 and 22, the gases are kept in contact with the bank of tubes and the under side of the water drum 10 for a longer time. When employing highly volatile fuels, both auxiliary baffles 25 and 26 may be used with the combined effects of those ascribed to each, namely the retardation of the gases which permits them to circulate upon the heating surfaces of the boiler for a longer period of time whereby a greater proportion of their heat is given up to the water in the boiler.

In Fig. 2 an auxiliary or alternative installation is illustrated. Here the lower baffle 19' does not extend along the lowermost row of tubes, but is spaced from the lower tubes so as to expose the lowest rows of tubes to the radiant heat issuing from grate 17. This arrangement is particularly adapted for burning low volatile fuels, such as anthracite, coke-breeze, lignite or the like. Extending at an angle across the lower tubes from the free rear end of lower baffle 19' is a second apron baffle 27. This whole lower baffle, including 19' and 27, may be used auxiliary to the upper baffle, 20—22, or may be an alternative arrangement, leaving upper baffle 20 without the apron 22, as in the usual installation.

During operation of the furnace, such volatile gases as are emitted by the fuel in grate 17, collect in the pocket formed between baffles 19' and 27, and are ignited either by the flame in grate 17 or the incandescence of portions of baffle 19'. These ignited gases are then deflected downwardly as a curtain which slowly descends over the lowermost tubes, thereby imparting their heat to these tubes. This curtain of gases is then caught by the draft and carried along with the remaining gases below the lower edge of apron baffle 20, so as to pass through passage 18 into the rear end of the bank of tubes. As these gases are deflected downwardly by the angular apron baffle 27, they may be employed to impinge

upon superheater 28, of any suitable design, placed below the rear end of the boiler. While a pocket is formed between baffles 19' and 27, the angularity of baffle 27 is such that no gases can be trapped in the pocket so that their explosion will rupture the boiler tubes or the baffles. 70

The baffle arrangement of this invention as applied to a horizontal water-tube boiler accordingly materially increases the rating of the boiler by procuring greater thermal efficiency. The baffles are so arranged that no closed pockets are formed wherein explosions of unburned gases upon opening the draft can occur, whereby the baffles are not liable to be blown out or cracked by explosion, and strain and rupture of the tubes due to this cause is prevented. Inasmuch as the transfer of heat to the boiler is increased by the new baffle arrangement, less heat is lost in the flue gases than heretofore, and in one instance, the temperature of the flue gases has been reduced from 750° to 450° F. upon installation of the new baffle arrangement. This retardation of the flow of the gases also permits more complete combustion so that greater fuel economy is provided as well as a decrease in the volume and density of the smoke. These and other advantages are obtained by this invention, and although a particular arrangement of the baffles has been described and illustrated, it is to be understood that it lies within the scope of the invention to make such alterations in the baffle arrangement as may be necessary to meet the various conditions of use. 100

I claim:

1. In combination with a boiler of the horizontal tube type, a substantially horizontal baffle extending along the lower tubes from the front to within a distance of the rear of the boiler so as to leave a gas passage into the bank of tubes, a second baffle extending along the upper tubes from the rear to within a distance of the front of the boiler so as to leave a gas passage from the bank of tubes, and a third baffle extending at an obtuse angle from the free end of the second baffle and crossing a portion of the tubes of the bank, the space between the end of the third baffle and the front of the boiler being substantially equal to the space between the end of the third baffle and the first baffle. 105

2. In combination with a boiler of the horizontal tube type, a substantially horizontal baffle extending along the lower tubes from the front to within a distance of the rear of the boiler so as to leave a gas passage into the bank of tubes, a second baffle extending along the upper tubes from the rear to within a distance of the front of the boiler so as to leave a gas passage from the bank of tubes, a third baffle extending at an obtuse angle from the free end of the second baffle and crossing a portion of the tubes of the bank to form a restricted passage, and a flue, the area of the 110 120 125 130

last-named passage and the area of the flue being substantially equal.

3. In combination with a boiler of the horizontal tube type, a substantially horizontal baffle extending longitudinally along the upper tubes for the greater part of their length from one end of the boiler, a second baffle extending downwardly from the free end of the first baffle across a portion of the tubes, and a third baffle extending upwardly from the opposite side of the first baffle approximately at the junction of the first and second baffles.

4. In combination with a boiler of the horizontal tube type, a substantially horizontal baffle extending longitudinally along the upper tubes for the greater part of their length from one end of the boiler, a second baffle extending downwardly from the free end of the first baffle across a portion of the tubes, a flue, and a third baffle above the tubes extending downwardly toward the first baffle and spaced therefrom, the third baffle being arranged in the passage between the second baffle and the flue.

5. In combination with a boiler of the horizontal tube type, a substantially horizontal baffle extending longitudinally along the upper tubes for the greater part of their length from one end of the boiler, a second baffle extending downwardly from the free end of the first baffle across a portion of the tubes, a flue, a third baffle extending upwardly from the opposite side of the first baffle into the passage between the second baffle and the flue, and a fourth baffle extending downwardly toward the first baffle and spaced therefrom, the fourth baffle being arranged between the third baffle and the flue.

6. In combination with a boiler having a bank of substantially horizontal tubes, a fire box below the tubes, a flue, a substantially horizontal baffle extending along the lower tubes adjacent the fire box from one end of the boiler to within a distance from the other end, a second similar, substantially horizontal baffle extending in the opposite direction along the upper tubes of the bank, a third baffle extending downwardly from the free end of the second baffle into the bank of tubes, a fourth baffle extending upwardly from the second baffle, and a fifth baffle extending downwardly toward the second baffle and spaced therefrom, the fourth and fifth baffles being arranged in the passage between the third baffle and the flue so as to impart a sinuous path to the furnace gases.

In testimony whereof I affix my signature.
SANFORD C. SMITH.
